UNITED STATES PATENT OFFICE.

DANIEL M. COOPER, OF ROCHESTER, NEW YORK, ASSIGNOR TO AMERICAN LAUNDRY MACHINERY COMPANY, OF CINCINNATI, OHIO, A CORPORATION OF OHIO.

PRESSING-MACHINE.

1,139,346.

Specification of Letters Patent. Patented May 11, 1915.

Application filed April 8, 1912. Serial No. 689,156.

To all whom it may concern:

Be it known that I, DANIEL M. COOPER, of Rochester, in the county of Monroe and State of New York, have invented certain new and useful Improvements in Pressing-Machines; and I do hereby declare the following to be a full, clear, and exact description of the same, reference being had to the accompanying drawings, forming a part of this specification, and to the reference-numerals marked thereon.

The present invention relates to improvements in pressing machines, having reference more particularly to the type of machine employed for ironing underwear, and similar flat pieces of work, and embodying generally a stationary heated bed, a presser adapted to be moved into and out of engagement with the bed, and a work holder arranged for movement between the bed and presser to support the goods during the pressing operation, and it has for its object to provide a machine in which the goods can be constantly fed to the machine with great rapidity.

A further object of my invention is to provide a machine which uses a removable work holder, so that one operator can be positioning the goods on the work holders, while another operator can feed the holders successively into the machine, thus enabling a continuous operation and permitting a large amount of work to be done on one machine.

Another object of my improvements is to provide means whereby the entire operation of the machine can be effected by a single movement of a treadle, or controlling device, which serves to set in operation a mechanism, operating in the first instance to feed the goods to a point between the presser and the bed, and subsequently to move the presser into engagement with the bed, the presser being retained in engagement for a predetermined length of time.

To these and other ends the invention consists in certain improvements and combinations of parts, all as will be hereinafter more fully described, the novel features being pointed out in the claims at the end of the specification.

In the drawings: Figure 1 is a view in side elevation of a machine constructed in

accordance with a preferred embodiment of my invention, the work holder appearing in 55 dotted lines; Fig. 2 is a plan view of the same showing a work holder in position to be fed; Fig. 3 is an end elevation; Fig. 4 is an elevation, looking at the opposite end of the machine; Fig. 5 is a plan view of a portion 60 of the controlling mechanism; Fig. 6 is a view in side elevation of the same; Fig. 7 is a sectional view on the line 7—7 of Fig. 5; Fig. 8 is a sectional view on the line 8—8 of Fig. 5; Fig. 9 is a sectional view on the line 65 9—9 of Fig. 5; Fig. 10 is a transverse sectional view of the clutch which controls the operation of the presser; Fig. 11 is a sectional view on the line 11—11 of Fig. 5; Fig. 12 is an enlarged view, in elevation, of 70 a portion of a work holder and the frame on which it travels; Fig. 13 is an enlarged sectional view, taken transversely through the frame, and showing one of the guide-ways and the feeding device which moves 75 therein; Fig. 14 is a longitudinal, vertical sectional view through the frame, showing one of the feeding devices; Fig. 15 is a detail view showing the connection between the switch arm and the rock shaft controlling the latter; Fig. 16 is a view in elevation of the retaining means for holding the switch arm in its several positions, and Fig. 17 is a view in elevation of the switch which controls the operation of the presser. 85

Similar reference numerals throughout the several figures indicate the same parts.

In the present embodiment, which illustrates a convenient and preferred arrangement for adapting the improvements to a 90 machine, the invention comprises a frame generally, which includes the base 1, the upright portions 2 to which are attached the standards 3, the latter carrying the supporting head 4 on which is mounted the stationary bed 5. The bed 5 may be heated in any suitable manner, as well known in this type of machinery, and while I have shown the bed arranged above the presser, the presser being movable upwardly to engage the bed, 100 it will be understood that this arrangement may be reversed, while still carrying out the features of my invention. Attached to the upright portions 2 are braces 6 and 7 which support the guide-ways or brackets 8 105 in which the feeding devices move. The

presser is designated at 9, being suitably mounted on the sleeves 10 which are arranged for vertical movement on the aforementioned standards 3. The presser is also 5 heated, preferably by circulation of steam through the pipes 11 in the usual manner.

The goods are fed longitudinally of the machine to a position between the stationary bed and the presser, the latter being thereupon 10 raised to engage the bed, as will hereinafter be described, and for the purpose of supporting and feeding the work, I provide, in the present embodiment, a rectangular frame 12 which supports a web 13 of 15 canvas or like material that is held in the frame by means of lacing 14, and for convenience throughout the remainder of this description, I will refer to this part as the work holder. The machine is so arranged 20 as to accommodate two such work holders simultaneously, and as one work holder is fed to pressing position, the work holder last operated on is ejected from pressing position by the first work holder. Any number 25 of work holders may be employed, and these may be filled with work at the convenience of the operators so that one will always be ready to go in the machine, and in this way much more can be accomplished 30 than if the work holder were a permanent part of the mechanism. This is an important feature of my improvement, although it is to be understood that the construction and operation of the presser actuating 35 means that will be hereinafter described, as well as other features of the machine, are not necessarily limited in their use to a machine embodying a removable work holder as described, but might be employed to good 40 effect in a machine where a continuous conveyer, or other means than that herein described, is used for supporting the work.

The work holders are suitably supported on the side rails 15, being arranged above a 45 table 16 and are adapted to be moved longitudinally of the frame by means of feeding devices, which, in the present embodiment, consist of the members 17 engaging in the guide-ways 8 and having projections 18 which extend upwardly beyond the table 16 and are in position to engage the work holder. The feeding devices are arranged to be moved longitudinally of the frame by suitable treadle controlled operating means 55 having connection with the feeding devices, and I will now describe a preferred form of said operating means, as disclosed in the present embodiment.

A normally stationary member, comprising a shaft 19, is connected to the feeding device, and to this end carries crank arms 20 having crank pins 21 engaging slots 22 in the levers 23, the latter being pivotally mounted at 24 and connected to the feeding 60 devices by means of the connecting rods 25.

The shaft 19 is adapted to be operated by a constantly driven member, which in the present embodiment, comprises the disk 26 fixedly mounted on a hollow shaft 27, the latter also having keyed thereto a worm 70 wheel 28 with which engages the worm gear 29, the latter being fixed on the motor shaft of the continuously driven motor 30. The shaft 19 is actuated from the disk 26, upon the operation of a suitable controlling device, preferably in the form of a treadle 31, which is arranged to actuate a clutch between the disk 26 and the member 32, which is keyed on the shaft 19. To this end, the disk 26 carries a plurality of projections 33 80 while the member 32 has pivotally mounted thereon a clutch 34 controlled by a spring 35, the latter serving to draw the clutch into operative position where it engages one of the projections 33. The clutch is normally 85 held in inoperative position by means of the releasing member 36 which is mounted on the rock shaft 37. The latter has fixed thereon the arm 38 to which is pivotally connected a rod 39, which is in turn connected 90 to the treadle 31 by means of an arm 40 mounted on a rock shaft 41, carrying the aforementioned treadle 31. The treadle is preferably provided with a suitable weight 42 to return it to normal position. From 95 this, it will appear, that upon pressing the treadle 31, the clutch 34 is released and locks the member 32 with the constantly rotating disk 26, thereby causing the shaft 19 to turn through a complete revolution, and this 100 through the crank arms 20 and levers 23, reciprocates the connecting rods 25, and moves the feeding devices longitudinally of the frame sufficiently to move the work holder from the position shown in dotted 105 lines in Fig. 1 to the pressing position between the bed and presser. At the same time, the work holder that is already in pressing position and have just previously been operated on, is ejected from its pressing position beneath the bed, to the delivery end of the machine by the advancing 110 work holder.

The presser is operated subsequently to the movement of the feeding devices, and 115 by means of instrumentalities controlled by the movement of the feeding devices, as will now be described. In the present embodiment, the presser 9 is adapted to be moved upwardly by means of the plunger 43 which 120 carries an adjustable engaging portion 44 and is provided with arms 45 having rollers 46 at their outer ends for engagement with the ways 47. The plunger 43 is supported by means of a toggle joint, consisting of the 125 toggle links 48 and 49, respectively, and knuckle 50, the latter being arranged in the recess 51 of a traveling block 52 which is threaded interiorly and is arranged to be engaged by a rotary screw 53 mounted on 130

the shaft 54. Said shaft 54 carries the gear wheel 55 meshing with the pinion 56 which is mounted on the motor shaft of the electric motor 57. The presser is first raised, 5 being held in pressing position for a predetermined length of time, and thereafter lowered, and to this end, means are provided for operating the motor 57 first in one direction, permitting it to remain idle for a predetermined length of time, and thereafter 10 reversing its movement. This operation is preferably controlled by means of an electric switch comprising stationary contacts 58 which are suitably connected with the 15 motor by circuits 59, as shown. The motor is operated by closing one or the other of the circuits 59 through a movable contact 60 which is mounted on the shaft 61 to which is fixedly secured the switch arm 62. 20 The switch arm 62 is pivotally connected by means of link 63 with a rock-arm 64 which is loosely mounted on the rock shaft 65. Fixedly attached to said rock shaft 65 is a yoke member 66 carrying springs 67 which 25 engage the opposite sides of the projection 68, the latter being fixed on the rock-arm 64. The purpose of this construction is to provide a yieldable connection between the rock shaft 65 and the link 63. The rock 30 shaft 65 is arranged to be moved alternately in opposite directions, and to this end carries the arm 69 which is engaged and operated by a normally stationary member in a manner that I will now describe. 35 The hollow shaft 27, which is constantly driven from the motor 30 through worm wheel 28, carries a worm gear 70 which meshes with the worm wheel 71 fixed upon the shaft 72. The shaft 72 carries a clutch 40 member 73 which is fixed thereon and provided with a series of notches or recesses 74. The clutch member 73 co-operates with a normal stationary member, the latter in the present embodiment comprising the disk 75 45 which is loosely mounted on the shaft 72 and carries two pairs of oppositely disposed abutments 76, said abutments being mounted on plates 77 which are adjustably attached to the disk 75 by means of the slots 78 and suitable securing means. The disk 50 75 has pivotally mounted thereon a pair of clutches 79 connected by the link 80 and arranged to be actuated by the springs 81. Each of said clutches is provided with a 55 tail piece 82, and 83 designates a releasing member mounted on the rock shaft 84 and adapted to engage one of the tail pieces 82, as shown in Fig. 7, to hold the clutches 79 normally in inoperative position. The rock 60 shaft 84 has fixed thereon the weighted arm 85 which is arranged to be engaged by the lever 86, the latter being mounted on the shaft 19 and adjustably held in fixed relation to the member 32 by means of the slot 65 87 and nut 88, as shown in Fig. 6. Thus, after the treadle 31 is actuated to cause movement of the feeding devices, as the shaft 19 turns, the lever 86 engages the arm 85 at such an instant with relation to the turning of shaft 19, that the feeding devices 70 will have completed their inward movement and be almost in their normal positions. This operates the rock shaft 84 and releasing member 83, and thus permits the clutches 79 to engage clutch member 74 and rotate 75 the disk 75, for half a revolution, or in other words, until the opposite abutment 82 reaches the releasing member and engages the same. During this half revolution of the disk 75, the arm 69 on rock shaft 65 is 80 operated alternately in opposite directions by the two oppositely disposed abutments on one half of the disk 75. This movement of the rock shaft 65 is communicated to switch arm 62, moving the same first in one 85 direction and then in the opposite direction, whereby the motor 57 is operated alternately in opposite directions to first raise the presser and subsequently lower the presser. By adjusting the abutments 76 on 90 the disk 75, the time during which the presser is held in engagement with the bed may be changed to suit the demands of the machine. In order to hold the movable contact of the switch in its adjusted position, I 95 preferably mount on the rock shaft 61 a locking plate 89 provided with a series of notches 90 which are arranged to engage an abutment on the pivotally mounted spring controlled retaining member 91. By this 100 means, when the rock shaft 65 is operated to move the switch arm in one direction or the other, the latter is held in such position by the retaining member 91, causing the motor to operate in the corresponding direction, until the switch arm is moved to its normal or intermediate position, as shown in Fig. 3. To accomplish this last result, I provide on the block 52 a vertical extension 105 92 which carries the stop-bar 93 on which 110 are the adjustably mounted stops 94. In the operation, when the presser reaches the limit of its movement either upwardly or downwardly, the block 52 will have reached such a position as to cause one of the stops 94 to 115 engage the switch arm 62 and return it to its normal intermediate position. 120 In the position shown in Fig. 3, the presser has just reached the limit of its upward movement and is in engagement with the bed, the switch arm 62 having just been returned to its normal position by the nearest stop 94. The presser will remain in this position until the disk 75 has rotated far enough to actuate the rock shaft 65 and 125 thereupon throw the switch arm 62 in the opposite direction so as to reverse the direction of the motor 57 and lower the presser. At the end of the downward movement of the presser, the switch arm 62 will be en- 130

gaged by the other abutment 94 and returned to its normal position, thus cutting out the motor. The parts then remain stationary until another operation of the treadle 31.

5 It is desirable to retard and stop the movement of the screw 53 when the motor 57 stops, and to this end, I mount on the shaft 54 a brake disk 95 which is arranged to be engaged on opposite sides by the pivotally 10 mounted braking member 96, the latter being operated by means of a rod 97 passing therethrough and connected to the block 52. Springs 98 and 99 are provided on the rod 97 on opposite sides of the braking member 15 96, so as to provide a resilient connection and prevent any undue jarring or straining of the parts, while at the same time stopping the movement of the screw 53 immediately upon the operation of the controlling switch.

20 It is possible that the operator might inadvertently depress the treadle while the presser is raised which would cause serious injury to the machine, and to prevent this, I provide a locking device which is thrown 25 into operation when the presser is raised, to prevent movement of the feeding devices. To this end, the arm 38 carries an upwardly extending portion 100, arranged to be engaged by the weighted latch 101. Said latch 30 101 is pivoted at 102 and carries a tail piece 103, which is in position to be engaged by a rod 104 mounted on the presser. Normally, when the presser is lowered, the latch is raised, as shown in full lines in Fig. 6, and 35 when the presser is raised, the latch falls, as shown in dotted lines, engaging the portion 100 on arm 38, and preventing movement of said arm. The feeding devices thus cannot operate, except when the presser is 40 lowered.

I claim as my invention:

1. In a pressing machine, the combination with a frame, of a bed, a presser movable vertically of the frame and coöperating with 45 the bed, feeding devices movable longitudinally of the frame, means having connection with the feeding devices for moving the latter, and instrumentalities controlled by the movement of the last mentioned means for 50 operating said presser.

2. In a pressing machine, the combination with a frame, of a bed, a presser movable vertically of the frame and coöperating with the bed, feeding devices movable longitudinally of the frame, means for moving the 55 feeding devices, and instrumentalities controlled by said means for operating the presser, said instrumentalities being brought into operation after the movement of the 60 feeding devices.

3. In a pressing machine, the combination with a frame, of a bed, a presser movable vertically of the frame and coöperating with the bed, feeding devices movable longitudinally of the frame, operating means acting 65

first to effect movement of the feeding devices and subsequently to actuate the presser, and a controlling device connected to said operating means.

4. In a pressing machine, the combination 70 with a frame, of a bed, a presser movable vertically of the frame and coöperating with the bed, feeding devices movable longitudinally of the frame, and treadle-controlled operating means acting first to effect movement of the feeding devices and subsequently 75 to actuate the presser.

5. In a pressing machine, the combination with a frame, of a bed, a presser movable vertically of the frame and coöperating with 80 the bed, reciprocatory feeding devices movable longitudinally of the frame, means for effecting movement of the feeding devices, and instrumentalities controlled by said means and operatively connected to the 85 presser for moving the latter, the last mentioned instrumentalities being brought into operation after the movement of the feeding devices.

6. In a pressing machine, the combination 90 with a frame, of a bed, a presser movable vertically of the frame and coöperating with the bed, feeding devices movable longitudinally of the frame, a normally stationary member adapted to impart movement to the 95 feeding devices, and a second normally stationary member adapted to control the movement of the presser, treadle-controlled means for operating the first mentioned normally stationary member, and means actuated by 100 the movement of the latter for operating the second normally stationary member.

7. In a pressing machine, the combination with a frame, of a bed, a presser movable vertically of the frame and coöperating 105 with the bed, feeding devices movable longitudinally of the frame, an electric motor for actuating the presser, a switch controlling the motor, and operating means for effecting movement of the feeding devices, 110 said means being operatively connected to the aforementioned switch to control the position of the latter.

8. In a pressing machine, the combination with a frame, of a bed, a presser movable 115 vertically of the frame and coöperating with the bed, feeding devices movable longitudinally of the frame, an electric motor for actuating the presser, a switch controlling said motor, and operating means acting 120 first to effect movement of the feeding devices and subsequently to operate said switch.

9. In a pressing machine, the combination with a frame, of a bed, a presser movable 125 vertically of the frame and coöperating with the bed, feeding devices movable longitudinally of the frame, an electric motor for actuating the presser, a switch controlling said motor, operating means acting 130

first to effect movement of the feeding devices and subsequently to operate said switch, and a treadle connected to said operating means for controlling the same.

5. 10. In a pressing machine, the combination with a frame, of a bed, a presser movable vertically of the frame and coöperating with the bed, feeding devices movable longitudinally of the frame, an electric motor 10 connected to the presser and adapted to operate alternately in opposite directions to raise and lower the presser, a switch controlling the movement of said motor, a switch arm, and operating means, acting 15 first to effect movement of the feeding devices, said operating means being connected to the switch arm and acting to move the latter alternately in opposite directions subsequently to the actuation of the feeding 20 devices.

11. In a pressing machine, the combination with a frame, of a bed, a presser movable vertically of the frame and coöperating with the bed, feeding devices movable longitudinally of the frame, operating means for effecting movement of the feeding devices, and instrumentalities controlled by said operating means for actuating the presser, said instrumentalities including a 25 toggle joint supporting the presser, a traveling block actuating the toggle joint, an electric motor operatively connected to said traveling block, a switch controlling said motor, a switch arm adapted to be moved 30 alternately in opposite directions, and means carried by the traveling block for returning the switch arm to normal position.

12. In a pressing machine, the combination with a frame, of a bed, a presser movable vertically of the frame and coöperating 40 with the bed, feeding devices movable longitudinally of the frame, operating means for effecting movement of the feeding devices, and instrumentalities controlled by 45 said operating means for actuating the presser, said instrumentalities including a toggle joint supporting the presser, a traveling block actuating the toggle joint, an electric motor operatively connected to said 50 traveling block, a switch controlling said motor, a switch arm adapted to be moved alternately in opposite directions, a spring controlled retaining member coöperating 55 with the switch arm, and means carried by the traveling block for returning the switch arm to normal position.

13. In a pressing machine, the combination with a frame, of a bed, a presser movable vertically of the frame and coöperating 60 with the bed, feeding devices movable longitudinally of the frame, operating means for effecting movement of the feeding devices, and instrumentalities controlled by 65 said operating means for actuating the presser, a locking device coöperating with

the operating means to prevent movement of the feeding devices when the presser is in engagement with the bed, and means carried by the presser acting to control said locking device.

70

14. In a pressing machine, the combination with a frame, of a bed, a presser movable vertically of the frame and coöperating with the bed, feeding devices movable longitudinally of the frame, operating means for effecting movement of the feeding devices, and instrumentalities controlled by said operating means for actuating the presser, said instrumentalities including a toggle-joint supporting the presser, a traveling block 80 actuating the toggle-joint, a rotary screw in engagement with said block, and means for rotating the screw alternately in opposite directions for predetermined periods of time.

85

15. In a pressing machine, the combination with a frame, of a bed, a presser movable vertically of the frame and coöperating with the bed, feeding devices movable longitudinally of the frame, a toggle-joint supporting the presser, a traveling block actuating the toggle-joint, a rotary screw in engagement with said block, and treadle-controlled means for effecting movement of the feeding devices and subsequently rotating the screw alternately in opposite directions for predetermined periods of time.

90

16. In a pressing machine, the combination with a frame, of a bed, a presser movable vertically of the frame and coöperating with the bed, feeding devices movable longitudinally of the frame, and treadle-controlled means for first effecting movement of the feeding devices, and subsequently moving the presser toward the bed, retaining the presser in pressing relation for a predetermined period of time, and finally moving the presser away from the bed.

105

17. In a pressing machine, the combination with a frame, of a bed, a presser movable vertically of the frame and coöperating with the bed, reciprocatory feeding devices movable longitudinally of the frame, a rotating member, a normally stationary member, a treadle-controlled clutch adapted to connect said members, and operative connections between the feeding devices and said normally stationary member.

110

18. In a pressing machine, the combination with a frame, of a bed, a presser movable vertically of the frame and coöperating with the bed, feeding devices movable longitudinally of the frame, a rotating member, a normally stationary member, a treadle-controlled clutch adapted to connect said members, connecting rods leading from the feeding devices, pivotally mounted slotted links having connection with said connecting rods, and crank arms carried by the normally stationary member and coöperating with said 125 130

slotted links to reciprocate the connecting rods.

19. In a pressing machine, the combination with a frame, of a bed, a presser movable vertically of the frame and coöperating with the bed, guideways extending longitudinally of the frame, feeding devices adapted to move in said guideways, a rotating member, a normally stationary member, 10 a treadle-controlled clutch adapted to connect said members, and operative connections between the feeding devices and the normally stationary member.

20. In a pressing machine, the combination with a frame, of a bed, a presser movable vertically of the frame and coöperating with the bed, feeding devices movable longi-

tudinally of the frame, operating means for effecting movement of the feeding devices, and instrumentalities controlled by said operating means for actuating the presser, said instrumentalities including an electric motor operatively connected to the presser, a switch controlling the motor, a switch arm, a rock-shaft connected to the switch arm, a 20 rotatable disk adapted to be set in motion by said operating means, and abutments adjustably mounted on the disk and coöperating with said rock-shaft to move the same alternately in opposite directions.
